UNITED STATES PATENT OFFICE

169,057

CHAIN LINK OR SIMILAR ARTICLE

Alpin Chisholm, Attleboro, Mass.

Application October 30, 1952, Serial No. 22,057

Term of patent 14 years

(Cl. D45—4)

To all whom it may concern:

Be it known that I, Alpin Chisholm, a citizen of the United States of America, residing in Attleboro, in the county of Bristol and Commonwealth of Massachusetts, have invented a new, original, and ornamental Design for a Chain Link or Similar Article, of which the following is a specification, reference being had to the accompanying drawing, forming a part thereof.

Fig. 1 is a front elevational view of a chain link embodying my new design;

Fig. 2 is a side elevational view thereof; and

Fig. 3 is a top plan elevational view thereof.

I claim:

The ornamental design for a chain link or similar article, substantially as shown.

ALPIN CHISHOLM.
